UNITED STATES PATENT OFFICE

2,410,810

DIAPHRAGM CONSTRUCTION FOR
TURBINES

Val Cronstedt, Marlboro, Conn., assignor to
United Aircraft Corporation, East Hartford,
Conn., a corporation of Delaware

Application July 23, 1943, Serial No. 495,931

5 Claims. (Cl. 253—78)

1

This invention relates to turbines and particularly to the aligning of the split sections of the turbine diaphragms.

When a turbine is made up of several rows of diaphragms with nozzles, alternating with rows of rotating blades, the diaphragms are generally split to permit assembly of them with the rotor on which the blades are mounted. The inner portion of the split edges cannot be reached for fastening after assembly to the rotor. A feature of this invention is the maintenance of alignment of the edges of the diaphragms. This is particularly desirable in gas turbines subjected to large temperature variations.

Many turbines carry sealing rings at the inner edge of the diaphragm. Another feature of the invention is the support of these sealing rings in the diaphragm. The co-pending application of Cronstedt and Ledwith, Serial Number 486,619 filed May 11, 1943, shows a turbine in which the casing is made up of a number of rings, each of which has an integral diaphragm. A number of these casing rings are split for assembly purposes, and the outer edges of adjoining rings are connected to form the casing. A feature of this invention is the use of stepped pins at the inner edge of each diaphragm to hold the opposed halves of each casing ring in alignment.

Other objects and advantages will be apparent from the specification and claims, and from the accompanying drawings which illustrate what is now considered to be a preferred embodiment of the invention.

Fig. 1 is a sectional view through the turbine.

Fig. 2 is a transverse sectional view on line 2—2 of Fig. 1.

Fig. 3 is a sectional view through the front casing ring of Fig. 2 along line 3—3.

The turbine shown includes a casing 10 built up of rings 12, 14, 16 and 18 supported by radial pins 20 in a housing 22 and engaging bores in bosses 24 in the casing. These pins are all in substantially the same plane and constitute the sole support for the casing. A shaft 26 with rows of blades 28 thereon rotates in proximity to nozzles 30 forming part of the diaphragms 32 integral with the casing rings.

Housing 22 has a head 34 which forms a part of the housing and supports a bearing sleeve 36 for the front end of shaft 26. At the other end of the turbine, housing 22 has a spider 38 within which is a bearing 40 for the shaft. The spider has a number of legs 42 engaging radial pins 44 in the housing.

The diaphragm 32 which is integral with each

2

casing ring has, in addition to the nozzles, a disc 46 which extends inwardly from the row of nozzles. This disc carries at its inner edge a sealing ring 48. The nozzles in adjacent diaphragms alternate with the rows of blades on the shaft.

Casing rings 14, 16 and 18 are split on radial planes, bolts 50 holding the halves of each split ring together at its outer periphery. The planes of the splits of adjoining casing rings may be staggered as shown in Fig. 2.

To maintain the sections of each split casing ring in alignment, disc 46 is provided with bores 52 which receive aligning pins 54. The bores 52 are located where the casing rings are split so that a part of each bore lies in each half of the disc forming opposed recesses which, when the ring sections are assembled, receive the pins, thus aligning the discs radially against distortions.

Disc 46 may have a radially extending groove 56 in its inner edge intersecting bores 52. Each pin has an enlarged central portion fitting within the groove and engaging opposite side walls of the groove to hold the parts of the diaphragm in axial alignment.

This groove 56 may receive a peripheral flange 58 on sealing ring 48 in which case the flange will have an opening 60 to receive the enlarged portion of each pin. As best shown in Fig. 2, the sealing ring is also split diametrically and is assembled with its split out of alignment with the split in the casing ring further to steady the diaphragm.

It is to be understood that the invention is not limited to the specific embodiment herein illustrated and described, but may be used in other ways without departure from its spirit as defined by the following claims.

I claim:

1. Means for aligning the split sections of a turbine diaphragm, each section having opposed recesses therein, said means including a pin fitting in said recesses, said pin extending axially of the diaphragm, and having an enlarged part engaging laterally with the diaphragm to hold the pin against endwise movement relative to the diaphragm and to hold the halves of the diaphragm in alignment.

2. Means for aligning the split sections of a turbine diaphragm, each section having opposed recesses therein, said diaphragm also having a groove in its inner surface with which the recesses intersect, and a seal having a flange overlapping the inner periphery of the diaphragm, said means including a pin engaging the opposed recesses and having an enlarged part fitting in

the groove, said flange having an opening with which a part of the pin engages.

3. Means for aligning the split sections of a turbine diaphragm, each section having opposed recesses therein, said diaphragm also having a groove in its inner surface with which the recesses intersect, and a seal having a flange in said groove, said means including a pin engaging the opposed recesses and having an enlarged part fitting in the groove and engaging opposite side walls of the groove, said flange having an opening with which the enlarged part of the pin engages.

4. A split turbine diaphragm having opposed sections in the adjoining edges of which are recesses, said diaphragm also having an annular groove in its inner periphery, a seal having a flange in said groove, and an axially extending

aligning pin engaging the recesses in the diaphragm and the flange of the seal, said flange having an opening to receive the pin, said pin having an enlarged portion fitting in said groove and engaging laterally with the walls of the groove for maintaining alignment of the diaphragm.

5. A split turbine diaphragm having opposed sections in the adjoining edges of which are recesses, said diaphragm also having an annular groove in its inner periphery, a seal having a flange in said groove, and an axially extending aligning pin engaging the recesses in the diaphragm and the flange of the seal, said seal being split and having its line of split out of alignment with the line of split of the diaphragm.

VAL CRONSTEDT.
